UNITED STATES PATENT OFFICE.

RICHARD STRESAU, OF WAUWATOSA, WISCONSIN, ASSIGNOR TO A. O. SMITH CORPORATION, OF MILWAUKEE, WISCONSIN, A CORPORATION OF NEW YORK.

THIN-GAUGE-METAL AUTOMOBILE FRAME.

Application filed April 18, 1921. Serial No. 462,017.

To all whom it may concern:

Be it known that I, RICHARD STRESAU, a citizen of the United States, and a resident of the city of Wauwatosa, county of Milwaukee, and State of Wisconsin, have invented a certain new and useful Improvement in Thin-Gauge-Metal Automobile Frames; and I do declare the following to be a clear, exact, and complete specification thereof, such as will enable persons skilled in the art to which the invention pertains to make and use the same, reference being had to the accompanying drawing for illustration of the manner in which my invention is reduced to a practical form.

My invention relates to an improved automobile frame and to the manufacture of the same.

Heretofore, in constructing automobile frames from pressed steel parts, including side bars, cross-bars and gussets, the sheet steel which has been used for many years in the manufacture of such frame parts, has necessarily been of a gauge to insure the desired degree of strength and durability in the frame. As a consequence of the observance of these requirements, the frame has been an element contributing an excess of weight to the automobile as a whole. Steels of various alloys have been used, having in mind the purpose of effecting a reduction in the weight of the frame, while preserving the necessary degree of strength therein, but it has not been considered feasible, however, to use steel plates below a minimum gauge, having due regard to substantial construction of the frame, and its ability to resist the strains incident to the operation of the automobile in which the frame is placed.

I have discovered, however, that by using alloyed molybdenum and chrome steel plates, the gauge of the plate material from which the frame is produced, may be reduced to approximately one-half of that which heretofore has been conservatively considered the minimum gauge within the limits of safety, and have thus effected a corresponding decrease in the weight of the frame. Steel of this nature possesses all of the required elements of strength by reason of the hardness of the plates, and at the same time the elasticity which is desirable

in structures of this class, is preserved in a proper degree.

But some difficulties have been encountered in properly connecting or attaching the adjunctive devices to the side bars of the automobile frame in a substantial manner, when such side bars are made from the thin plates described, by reason of the tendency of the rivets connecting the parts to shear off under the weight imposed thereon. This defect is due to the condition that the thin gauge of the harder steel plates now used in the manufacture of the side bars, reduces very materially the area of the bearing contact upon the rivets and lessens the effective resistance exerted by the latter, so that the rivets are subjected to increased pressure in the line of the greatest strain. This condition renders it difficult to avoid the tendency of the rivets to be cut under the vibrations to which the structure is subjected in the operation of the automobile.

Attempts to overcome the objection referred to, by increasing the number of rivets employed for the purpose of uniting the adjunctive devices to the side bars of the automobile frame, has necessitated a corresponding increase in the number of perforations in the side bars for the accommodation of the larger number of rivets. But resort to this practice has developed a serious counter-defect, which manifests itself in the weakening of the side bars in the lines of such perforations, and it has resulted that the side bar is much more liable to fracture at the point of union of the adjunctive device with the side bar, by reason of the weakened structure of the latter, due to the increased number of perforations therein.

After much study of the problem involved, and some experimentation, I have devised a new plan for connecting or attaching the adjunctive devices to the thin-gauge sheet metal side bars of an automobile frame, whereby I am enabled to effect a firm and rigid union between the parts and I attain this very satisfactory result without in any degree impairing the strength of the side bar at the point of such union.

I achieve the purposes of the invention by the employment of a system of electric welding, in the practice of which the said

adjunctive devices are rigidly attached to the side bars at points or in lines where the strains are neutral, and preferably I secure this result without resorting to the former and customary practice of perforating the side bars to provide for the attachment of such adjunctive devices.

As hereinbefore stated, the side bars are drawn from thin-gauge strips or plates of alloyed molybdenum and chrome steel, and formed into channels with angular flanges extending laterally of the vertically standing web and longitudinally of the side bar.

The adjunctive devices designed to be connected or attached to the side bar are similarly formed in their longitudinal dimensions, which extend transversely to the plane of the side bar, so as to closely or snugly embrace or engage the web and both flanges of the side bar. The flanges projecting lengthwise of the adjunctive devices ordinarily will be co-extensive with the lateral flanges of the side bar at the point of union with the latter. In such an arrangement, the longitudinal edges of the side bars and the transverse edges of the adjunctive device will be in alignment. The aligned edges are then welded together by the application of a fusing electric current, in connection with which a destructible weld-rod may be used if desired. The lines of welding thus produced lie in planes in which the strains upon the joints are entirely neutral.

The resulting construction is such that an integral and unitary structure is produced, the adjunctive devices being permanently united to the side bar without in any manner weakening the latter. On the contrary, the strength of the side bar not only is preserved, but is actually increased over that which exists in automobile frames constructed in accordance with the methods heretofore known. However, in some cases, the welding may be facilitated but not appreciably augmented by the employment of a comparatively small number of rivets which may be inserted for the purpose of effecting a close union between the webs of the parts; but the number of rivets employed for this purpose will be such that the side bar will not present any element of weakness at the points where the rivets are used.

I have herein referred to adjunctive devices as connected or attached to the side bars of the frame, and in the interest of clearness will state, that the term used is intended to apply to the spring hangers, cross bars or other elements which form necessary parts of a completed automobile frame, and which in the final assembly constitute permanent parts of the structure thereof.

The novel features of my invention will

be described later on in this specification, and will be particularly pointed out in the appended claims.

In the accompanying drawing,

Figure 1 is a perspective view of a section of a side bar of an automobile frame drawn from a thin-gauge steel plate, and illustrating the manner of attaching one of the adjunctive devices, such as a spring hanger, thereto in accordance with my present invention.

Fig. 2 is a similar view showing a modification in the construction of the attached adjunctive device.

Fig. 3 is a vertical sectional view on the line 3—3, Fig. 1, looking in the direction of the arrow.

Fig. 4 is a vertical sectional view through a side bar showing a modification in the manner of attaching the adjunctive device.

Fig. 5 is a vertical sectional view showing the manner of attaching the adjunctive device, in this instance a cross bar, to a side bar, the channel of which is arranged outwardly with respect to the automobile frame.

Fig. 6 is a vertical sectional view through a thin-gauge metal cross bar showing a means sometimes resorted to in attaching the adjunctive devices thereto.

As stated at the commencement of this specification, the present invention relates to the manner and means employed for connecting or attaching adjunctive devices, such as spring hangers, cross bars, or other elements, to the side bars of an automobile frame, which side bars are formed as channels from steel plates of thin-gauge.

In Fig. 1 the numeral 10 designates a side bar, such as I proposed to form from a thin-gauge plate of molybdenum and chrome steel, or other thin-gauge steel plate so alloyed as to possess the required maximum strength for the present purpose, notwithstanding the reduction of the gauge of the plate. In practice, I have found that steel plates so alloyed and having a gauge of .0625 possess the necessary elements of strength, and are entirely serviceable for use in manufacturing the frames of many types of pleasure cars. This reduction in the gauge of the plates is accompanied by a direct proportionate reduction in the weight of the frame, and consequently is a valuable factor in modern automobile construction, in which persistent efforts are being made to reduce the weight of the various parts thereof.

However, a serious difficulty has been encountered in the use of thin-gauge plates of the character described, in that the rivets employed in connecting or attaching the adjunctive devices to the side bars are subject to severance, by reason of the greatly reduced area of the bearing between such

rivets and the vertical webs of the side bars. As a result the attached adjunctive devices became loose and create a situation which may be disastrous if not discovered and 5 remedied.

The spring hanger 11 may be referred to as embodying a specific form of the adjunctive devices mentioned. These hangers are usually attached to the side bars by means 10 of rivets passing through registering perforations in the two parts. To overcome the objection adverted to, it has been proposed to increase the number of rivets used for connecting the parts, but this practice has 15 necessitated a corresponding increase in the number of perforations in the side bar, which perforations, by reason of their close grouping, have been found to materially weaken the side bar at the points of connection of the spring hanger thereto. The strains exerted are perpendicular to the plane in which the rivets extend, and the varying pressures of such strains due to 20 their relaxation under the changing conditions of the loads carried by the automobile, is productive of a tendency to a shearing action upon the rivets. Fig. 6 illustrates an expedient which has been resorted to in some cases with a view to meeting the 25 adverse situation described. In this figure, a reinforcing plate 12 is arranged within the channel in the thin-gauge side bar, the rivets passing through the spring hanger 11 and the plate 12, and clamping the web 30 of the bar 10 between the parts.

In carrying out my invention, I form the spring hanger so that the outlines thereof will correspond to those of the side bar, that is, the web 13 of the spring hanger 40 will bear against the vertical web of the side bar, while the longitudinally extending parallel flanges 14 of the spring hanger will embrace and closely engage the top and bottom flanges of the side bar. The 45 best results will be secured, and the manufacture will be facilitated, by making the width of the flanges of both parts co-extensive, so that their edges will be in vertical alignment, in the direction of the length 50 of the frame. Such aligned edges are united as at 15 by the process of electric welding, which welding operation may be effected with facility by any suitable electric welding machine. A fusible weldrod may be employed in the operation with good results, but the use of such weldrod is not necessary to the successful practice of my invention, 55 inasmuch as the aligned edges of the parts may be fused together by an arcing current delivered by any of the known forms of welding devices. In the construction described, the welding is effected in lines where 60 the strain upon the connection is entirely neutral, and the parts are united into a 65 homogeneous and permanent structure. It

is not necessary however, that the longitudinal flanges 14 of the spring hanger be co-extensive with the laterally extending flanges of the side bar at the points of attachment, but such flanges may be of a lesser 70 width and be united to the surfaces of the side bar flanges on lines removed from the edges of the side bar flanges. In fact, the welding may also be effected on lines which are transverse to the side bar, that is, along 75 the side edges of the flanges of the spring hanger, but it is not necessary to resort to this expedient, inasmuch as the longitudinal welding first described is ordinarily sufficient. In all of these cases, the welding 80 is effected on lines in which the strain upon the spring hanger is neutral.

If desired, two rivets indicated 16 in Figs. 1 and 3, may be used to secure accurate positioning of the parts and effect 85 a close engagement of the web of the spring hanger with that of the side bar. The use of so small a number of rivets will not weaken the side bar by reason of the perforations therein. 90

In Fig. 2 I have shown a construction in which the spring hanger 111 is attached to a short channel member 130, the latter being welded to the side bar in the manner previously described, the attachment of the 95 spring hanger 111 to the short channel member being effected by means of rivets or other devices prior to the operation of welding the spring hanger to the side bar. The gauge of the short channel member 130, 100 Fig. 2, will exceed some what that used in forming the integral spring hanger, Fig. 1, so as to resist the strains upon the rivets connecting the parts 111 and 130.

In Fig. 4 I have shown the side bar 10, with the spring hanger 112 arranged in the channel thereof, the aligned edges of the parts being welded at 15 as before, the webs and flanges of both parts bearing a close engagement, one fitting snugly within the 110 other, as in Figs. 1, 2 and 3.

In Fig. 5, the side bar 100 is arranged with the channel therein opening outwardly with respect to the automobile frame, this view showing also one end of a cross bar 101 with its projecting end flanges embracing the laterally extending flanges of the side bar, the aligned edges of the parts being welded at 15 as before. A lap 102 extending angularly with respect to the web 115 of the cross bar may be placed against the web of the side bar and welded thereto along the vertical edge of the lap. Also the longitudinal edges of the projecting end flanges of the cross bar may be welded to the side bar on lines transverse to the latter. 120

It is feasible also to additionally weld the spring hanger to the side bar in the vertical angles formed by the meeting of 130

the webs. Likewise, the union of the parts may be effected in an efficient manner by spot-welding the over-lapping flanges. Although I found it expedient to perform the welding operation by means of an electric arc, it is obvious that such welding may be accomplished by resort to other methods, the particular method of welding not being regarded as important in the practice of my invention.

In the practice of my present invention, I have produced an integral, homogeneous and unitary automobile frame with the adjunctive devices thereon in its final and permanent form, and the integrity of which cannot be destroyed during the life of the car in the construction of which it forms a most essential part. As has hereinbefore been pointed out, the advantages of a structure so produced are superior to those which result from the former attempts to manufacture frames of this class.

Having thus described my invention, what I claim and desire to secure by Letters Patent of the United States, is:

1. In an automobile frame, a pressed steel side bar of channel cross-section the longitudinal flanges of which extend angularly with relation to the web thereof, in combination with an attached adjunctive member having a contour which corresponds to that of the side bar and adapted to snugly engage the web and both flanges thereof, the said adjunctive member being welded to the side bar on lines longitudinally of the latter.

2. In an automobile frame, a pressed steel side bar of thin gauge material formed as a channel-section the flanges of which extend angularly with relation to the web thereof, in combination with an adjunctive attached member having a contour which corresponds to that of the side bar and adapted to snugly engage the web and both flanges thereof, the said member being welded to the side bar at a plurality of places to effect rigid attachment thereto.

3. In an automobile frame, a pressed steel side bar of channel cross-section the flanges of which extend angularly with relation to the web thereof, in combination with an attached adjunctive member having a contour which corresponds to the cross-section of the side bar and adapted to snugly engage the web and both flanges thereof, the flanges of the adjunctive member being coextensive with the flanges of the side bar, and the said side bar and member being welded together along their coinciding edges lengthwise of the side bar.

4. In an automobile frame, a pressed steel side bar formed as a channel section the flanges of which extend angularly with relation to the web thereof, in combination with an adjunctive attached member the contour of which corresponds to the cross-section of the side bar and adapted to snugly engage the web and both flanges thereof, the said member being welded to the side bar along the edges of the member.

5. In an automobile frame, a pressed steel side bar formed as a channel section the flanges of which extend in parallel planes at one side of the web of the bar, in combination with a member having corresponding parallel flanges engaging the flanges of the channel section and welded thereto along the edges of the said member.

6. In an automobile frame, a side bar formed as a channel of pressed-steel having flanges extending in the direction of the length of the bar, in combination with a spring hanger having flanges engaging the flanges of the side bar, and welded thereto along the edges of the flanges of the spring hanger to produce a unitary structure.

7. In an automobile frame, a pressed-steel side bar of channel cross-section and having flanges extending longitudinally of the bar, in combination with a spring hanger having flanges co-inciding with the width of the flanges of the side bar and fused along the aligned edges of said flanges to weld the parts together.

8. In an automobile frame, a pressed-steel channel side bar, in combination with a spring hanger having projecting flanges engaging the side bar and welded thereto along the edges of the flanges of the spring hanger in lines where the strain upon the hanger is neutral, to produce a unitary structure.

9. As a new manufacture, an automobile frame comprising a flanged pressed-steel channel side bar and a spring hanger having flanges engaging those of the side bar, the flanges of the side bar and spring hanger being welded together in planes where the strains are neutral, so as to constitute a unitary and permanent structure, substantially as described.

In testimony whereof, I have signed my name at Milwaukee, Wisconsin, this 11th day of April, 1921.

R. STRESAU.
